UNITED STATES PATENT OFFICE.

LUDWIG FUCHS, OF ROHRBACH, AUSTRIA-HUNGARY.

CENTRIFUGAL MACHINE.

No. 877,991.

Specification of Letters Patent.

Patented Feb. 4, 1908.

Application filed February 3, 1906. Serial No. 299,243.

To all whom it may concern:

Be it known that I, LUDWIG FUCHS, subject of the Emperor of Austria-Hungary, residing at Rohrbach, in the Province of Moravia, Empire of Austria-Hungary, have invented certain new and useful Improvements in Centrifugal Machines, of which the following is a specification.

This invention relates to improvements in centrifugal machine of the kind in which by lowering a lever the bottom of the centrifugal drum can be disengaged from the hook-shaped parts fitted on the spindle of the drum, whereby the bottom can be lowered so that the goods treated in the machine, for instance the fill-mass or the crystallized sugar-mass freed from syrup, can be discharged from the machine without stopping the drum. On the other hand the bottom of the drum can be raised during the filling of the same and thus produce the closing of the drum, and for this purpose it is only necessary to tread upon a foot lever connected with the bottom of the drum by means of a lever and a rod.

Now the improvements which form the subject matter of the present invention consist in that the raising of the movable bottom of the centrifugal drum is effected instead of by a lever mechanism by the pressure of a liquid or of a gaseous agent, whereby the construction of the machine is considerably simplified and the working of the same is rendered more reliable.

In the centrifugal machine of the old construction, hook-shaped parts are used for maintaining the bottom of the drum in its raised position. On account of the wearing out of these hook-shaped parts the reliability of the working of the whole machine becomes impaired. The application of water or gas pressure or of a vacuum, according to the present invention, for raising the bottom of the centrifugal drum affords the possibility to dispense entirely with the said hook-shaped parts. Moreover, since the improved machine does not comprise any rigid, immovable bearings, the spindle being mounted loosely, it works with a perfectly quiet motion and, besides, a strong foundation in masonry, which is absolutely indispensable for the old machine of this kind, to absorb the concussions, is unnecessary for the new machine. Whereas the old centrifugal apparatus can be mounted only on the ground floor, the improved machine can be

suspended between two girders of a floor or building.

The accompanying drawings represent the improved centrifugal machine in section Figure 1 showing the suitable arrangement of the machine when the pressure of a liquid medium is employed, whereas in Fig. 2 the machine is shown when gas pressure is employed. The raised position of the bottom of the centrifugal drum is shown in Fig. 65 1 in dotted lines; in Fig. 2 only those parts of the machine which refer to the invention are shown in section, all other parts being represented in side elevation.

On the spindle *a* of the centrifugal machine shown in Fig. 1 is arranged a belt-pulley *b* which serves for the reception of the plunger piston *c*. When the machine is worked by electricity the plunger piston is arranged within the collector. The plunger piston is raised by pressure-water fed from an elevated reservoir and flowing through a pipe *d* into the hollow spindle *a* and thence through a transverse channel *e* of the latter into the hollow recess made in the pulley *b*. The plunger is closed water-tight against the spindle and against the interior wall of the pulley by means of the leather collars *f* and *f'* respectively. In the upper end of the plunger is screwed a sleeve *g* which encompasses the spindle and passes through the bolster *h* of the same. On the upper end of the sleeve is screwed a ring *i* which acts upon the movable bottom *j* and upon the ring *r* fixed on four arms and raises the same as soon as pressure water is being admitted. Upon the hub portion of the belt-pulley *b* is arranged a leather ring *k* which has for its purpose to weaken the impact of the plunger upon the hub which takes place when the bottom of the drum is falling downwards. The guiding of the spindle is effected by groove and feather *l*. This guiding device as well as the upper bolster *h* of the spindle are lubricated by means of a consistent lubricating material fed from a lubricating cup *m* through the hollow spindle, whereas the upper ball-bearing *2*, receives its lubricating material from an oil cup *n*. The employment of pressure water has moreover the additional advantage of permanently maintaining the lower part of the spindle in a cool condition and thus obviating any possibility of the wearing off of the step bearing.

In order to close the centrifugal drum it is

only necessary to open the three-way-cock δ and to admit pressure-water into the hollow spindle a ; if now the cock is turned into its second position the water will flow off laterally, the bottom of the drum will move downwards and the fill mass or crystallized sugar mass freed from syrup will be discharged from the drum.

The employment of gaseous pressure agents renders certain modifications in the construction of the centrifugal machine necessary. These modifications refer principally to the particular arrangement of the plunger and of the parts surrounding the same and further in the arrangement of a fluid friction brake which weakens the impact when the bottom of the centrifugal drum is being raised.

The left hand side of Fig. 2 shows the arrangement of the machine when gases or vapors under pressure are employed, whereas the right hand side of this figure represents the arrangement adapted for working with vacuum.

The plunger piston is in this arrangement provided at its bottom with a tension spring p guided on the plunger-guiding sleeve q suitably prolonged downwards. In the top end of the plunger is screwed the sleeve g that is acting upon the bottom of the centrifugal drum and is made to slide upon the spindle a . On this sleeve g is arranged the casing t of a hydraulic brake provided with stuffing boxes $s s'$, the bottom flange t' of this casing being rigidly connected with the top flange of the guiding sleeve q screwed onto the plunger casing b . The brake casing t is provided on each side with a pressure regulating pipe u with stop-cock v and the lid of this casing has an opening which can be closed by a screw w . Within the casing t is arranged a sliding piston x rigidly connected with the sleeve g . The casing t is filled with glycerin through the opening in its cover, after the screw w has been unscrewed.

When in consequence of the admission of the pressure agent through the hollow spindle a the plunger piston c and together with the same the sleeve g will be raised, the piston x will also be raised and will force the glycerin through the pipes u into the lower part of the casing t . In consequence of the resistance which the piston x meets during its ascending motion the bottom of the centrifugal drum is pressed slowly and gradually against the drum and for the same reason the downward movement of the bottom will be gradual.

The right hand side of Fig. 2 shows the arrangement of the machine when it is worked by vacuum created in the hollow spindle and in the hollow of the plunger piston that is connected with the spindle by means of the channel e' , or in other words, when the rais-

ing of the plunger c and of the bottom of the centrifugal drum is effected by the atmospheric pressure. In this modified arrangement of the machine the belt-pulley b is shaped to constitute the casing of the plunger, and the latter bears against the hub y of the pulley b ; a stuffing box z being interposed between the said parts for assuring a tight closure; the bottom of the casing b has several, for instance four apertures 1 so that when a vacuum has been established in the interior of the plunger the outer atmospheric air will press upon the bottom of the plunger at 1 and will raise the same. In this modified arrangement of the machine also a hydraulic brake is provided for deadening the force of the impact.

I claim:

1. In a centrifugal machine the combination with a drum having a movable bottom adapted to be disengaged therefrom, of a hollow rotatable spindle carrying said drum, a pulley secured to said spindle, a hollow plunger arranged in said pulley and connected with the movable bottom of the drum and means to admit and withdraw fluid under pressure to and from the said plunger respectively to raise and lower the same together with the movable bottom of the drum at will.

2. In a centrifugal machine the combination with a drum, having a movable bottom, adapted to be disengaged from said drum, of a hollow rotatable spindle carrying said drum, a pulley secured to the said spindle, a hollow plunger arranged in said pulley, a sleeve secured to the said plunger and surrounding the said hollow spindle, a ring screwed to the upper end of said sleeve adapted to act on the movable bottom of the drum, and means to admit and withdraw fluid under pressure to and from the hollow plunger respectively, to raise and lower the same together with the movable bottom of the drum at will.

3. In a centrifugal machine the combination with a drum, having a movable bottom adapted to be disengaged from said drum, of a hollow rotatable spindle carrying said drum, a pulley secured to the said spindle, a hollow plunger arranged in said pulley, a connection between the said plunger and the said movable bottom, means to admit fluid under pressure to the said plunger through the said hollow spindle, so as to raise the said plunger and movable bottom, connected therewith, and packing rings between the said plunger and the said pulley on one side and the hollow spindle on the other side.

4. In a centrifugal machine the combination with a drum, having a movable bottom adapted to be disengaged therefrom, of a rotatable hollow spindle, a pulley attached thereto, a hollow plunger connected with the said movable bottom and arranged in the

pulley, means to admit fluid under pressure through the hollow spindle to the said plunger, and a hydraulic piston connected with the said plunger acting as a brake for the movements of said plunger.

5. In a centrifugal machine the combination with a drum, having a movable bottom adapted to be raised and lowered towards and away from the drum, of a rotatable hollow spindle, carrying the said drum, a pulley secured to the said hollow spindle, a hollow plunger arranged in said pulley, a sleeve connecting the said plunger with the said movable bottom, a hydraulic piston carried by the said sleeve to act as a brake on the movements of the said plunger and bottom, and a casing surrounding the said plunger and guiding the same.

6. In a centrifugal machine the combination with a drum, having a movable bottom adapted to be raised towards and away from said drum, of a rotatable hollow spindle, a pulley closed at its lower end and secured to the said spindle, a hollow plunger, a sleeve connecting said plunger and said movable bottom, means for producing a vacuum in

said hollow plunger, and small apertures provided in the closed lower end of the said pulley, to admit atmospheric pressure under the said plunger.

30

7. In a centrifugal machine the combination with a drum, having a movable bottom adapted to be raised towards and away from said drum, of a rotatable hollow spindle, a pulley closed at its lower end secured to the said spindle, a hollow plunger, a sleeve connecting said plunger and said movable bottom, means for producing a vacuum in said hollow plunger, and small apertures provided in the closed lower end of the said pulley, to admit atmospheric pressure under the said plunger and a hydraulic piston secured to the sleeve connecting the said plunger and movable bottom to retard the movements of the said last named parts.
